UNITED STATES PATENT OFFICE.

CHARITY M. BEESON BOLLER, OF BROWNSVILLE, WISCONSIN.

DESIGN FOR A WORK-TABLE.

SPECIFICATION forming part of Design No. 22,518, dated June 6, 1893.

Application filed April 14, 1893. Serial No. 470,381. Term of patent 3½ years.

To all whom it may concern:

Be it known that I, CHARITY M. BEESON BOLLER, a citizen of the United States, residing at Brownsville, in the county of Dodge 5 and State of Wisconsin, have invented a new and original Design for Work-Tables, of which the following is a specification.

My invention relates to a new and original design for work-tables, which is fully described hereinafter in connection with the drawing and specifically pointed out in the appended claim.

The drawing illustrates a work-table, embodying my design, shown in perspective.

5 The essential feature of my design consists in a central pedestal, a flat top upon the upper end of the pedestal, a lamp arranged at the center of the top, above the pedestal, and a spirally-disposed vine or cord, connecting the pedestal and lamp-body and continued upon the surface of the top.

Referring to the drawing: A represents the pedestal or standard; B the horizontal top arranged upon the upper end of the pedestal or standard; C the lamp disposed centrally upon

the top and over the upper end of the pedestal; and D the spirally-twisted vine or cord encircling the pedestal to the under side of the top, and reappearing at the upper surface of the top and spirally-disposed around the 30 lamp. The branches of this vine spread over the upper surface of the top and terminate in flowers, foliage, &c., the portion of the vine which encircles the lamp terminating, similarly in foliage, &c., which covers the main 35 portion of the surface thereof. The vine has the appearance of holding the lamp upon the top.

Having described my invention, what I claim is—

40 The design for a work-table, substantially as shown and described.

In testimony that I claim the foregoing as my own I have hereto affixed my signature in the presence of two witnesses.

C. M. BEESON BOLLER.
